COMBINED FLEXIBLE CLOSURE AND POURING SPOUT

Charles E. Wickman, Aurora, Ill., assignor to Anfinsen Plastic Moulding, Inc., Aurora, Ill., a corporation of Illinois

Filed Nov. 30, 1960, Ser. No. 63,042

Term of patent 14 years

(Cl. D58—26)

FIG. 1 is a perspective view of a combined flexible closure and pouring spout, in open position, showing my new design;

FIG. 2 is a top plan view thereof;

FIG. 3 is a side elevational view thereof;

FIG. 4 is a bottom plan view thereof;

FIG. 5 is an end elevational view as seen from the left of FIG. 3; and,

FIG. 6 is a perspective view thereof, showing it closed.

I claim:

The ornamental design for a combined flexible closure and pouring spout, as shown.
